[57] ABSTRACT

A method of controlling the water head of the working face in the pressurized-slurry sealed shield method of construction, said method of controlling the water head comprising the steps of detecting the water head of the working face with a pressure transmitter, transmitting said water head as an electric signal to a pressure regulator, comparing said electric signal with the set pressure at said regulator, converting the electric signal corresponding to the deviation between said first-named electric signal and said set pressure into a pressure signal, and transmitting said pressure signal from a controlling board as an excitation voltage to a variable-speed motor made up of an eddy current coupler and an induction motor to control the rotational speed of said motor, thereby changing the amount of water supplied by a pump.

METHOD OF CONTROLLING THE WATER HEAD OF THE WORKING FACE IN THE SHIELD METHOD OF CONSTRUCTION

This invention relates to a method of controlling the water head of the working face in the pressurized-slurry sealed shield method of construction.

The water head of the working face must be constantly maintained at a given pressure for preventing the caving in of the earth and sand in the pressurized-slurry sealed shield method. The method that was generally employed heretofore for controlling the water head of the working face was that consisting of detecting the concentration of the muddy slurry in the exhaust line and to adjust the degree of opening of the valves of either the water supply line or the slurry exhaust line accordingly. However, the fluctuation of the pressure at the working face was great in the case of this method due either to the inaccuracy of the detection of the concentration or to the considerable time that was required until the valves were opened in response to the fluctuation of pressure. In consequence, the collapse of the working face or clogging of the slurry exhaust line was likely to occur to inevitably result in the stoppage of the construction work.

Accordingly, an object of the present invention resides in ensuring that the water pressure necessary for maintaining the stability of the working face of the excavation is always maintained constant, thereby making it possible to carry the management of the pressurized-slurry sealed shield method safely and with certainty.

Other objects and advantages of the invention will become apparent from the following description.

I found that the foregoing objects of the present invention could be achieved if consideration was given to coupling a variable-speed motor to the water supply pump that delivers water to the working face and by varying the rotational speed of this motor and hence the amount of water supplied by the pump.

The present invention will now be specifically described by referring to the accompanying drawing, which illustrates one mode of practicing the invention. In the drawing, the solid lines represent the pipelines, while the broken lines represent the electric wiring.

Referring to the drawing, (1) is the water supply pump driven by means of an alternating-current variable-speed motor. The a. c. variable-speed motor is made up of a three-phase squirrel-cage induction motor (2) and an eddy current coupler (3). Since this setup is so adapted that by the application of a direct-current excitation to the excitation coil in the eddy current coupler (3), the torque of the induction motor (2) (input shaft) is transmitted to the eddy current coupler (3) (output shaft), the rotational speed of the variable-speed motor can be continuously varied by controlling the voltage of said d. c. excitation.

Water delivered by means of the water supply pump (1) enters the frontal cutter chamber (4). The soil excavated by the cutter (5) enters the chamber (4) where it becomes a muddy slurry and is discharged externally of the tunnel by means of an exhaust pump (6) (The numerals 2' and 3' are respectively an induction motor and an eddy current coupler as in the case with 2 and 3, above.). Now, since there is a variation in the concentration of the muddy slurry depending upon the amount of the soil excavated in this case, the pressure

inside the frontal cutter chamber (4) fluctuates. This pressure is detected by a pressure transmitter (7) and is transmitted in the form of a d. c. electric signal to a pressure regulator (8). The regulator (8) compares the electric signal value received from the pressure transmitter (7) with the set value of a pressure setting device (9) appended to the regulator (8) and sends to a pre-amplifier (10) as an operating output a d. c. electric signal (including a P. I. D. action) corresponding to the deviation in the foregoing values to convert the electric signal to a pressure signal. The pressure signal is transmitted via a controlling board (11) to the eddy current coupler (3) as an excitation voltage by which the rotational speed of the variable-speed motor (2 plus 3) and the amount of water supplied by the pump (1) are controlled.

On the other hand, a speed detecting generator (12) detects the speed of the eddy current coupler (3), and feeds back the detected speed as voltage to the controlling board (11). The controlling board (11) compares the detected voltage with the set voltage, adjusts the excitation voltage until there is no deviation in the two voltages and functions to maintain the established water pressure by varying the rotational speed of the variable-speed motor (2 plus 3) and the amount of water supplied by the pump (1) through adjustment of the speed of the eddy current coupler (3).

Even in those cases where the pressure of the frontal cutter chamber (4) changed owing to a change of the performance of the exhaust pump (6) resulting from a change in the concentration of the muddy slurry, the water supply pump (1), as hereinbefore noted, is automatically adjusted as to its rotational speed or number of strokes in response to the amount of slurry exhausted by the exhaust pump (6), thereby ensuring that water in an amount necessary to maintain a proper water head is supplied. In those instances where the emergency shutoff valve (13) is in operation, the rise in water head can be continuously controlled with great precision by the pressure transmitter (7) detecting the change in the water head and by the water supply pump (1) responding over broad range up to the established pressure to be maintained.

Since the controlling system of the present invention is set up as hereinbefore described, it is possible by setting the pressure setting device (9) appended to the regulator (8) at a prescribed water pressure and by detecting the fluctuation in water head of the working face with said pressure setting device, converting the water head fluctuation to a voltage fluctuation and transmitting this to the eddy current coupler, to accomplish minute adjustments in the number of strokes or rotational speed of the water supply pump (1) with a prompt response speed and thus control the amount of water supplied, which is necessary for maintaining the water head.

In the case of the method of controlling the water head of the frontal cutter chamber in the conventional pressurized-slurry sealed shield method, the water head that was necessary for maintaining the stability of the working face was difficult of maintaining constant at all times. Hence, there was a possibility of the caving in of the working face. On the other hand, in accordance with the present invention, the water head can be maintained constantly at the set pressure in accordance with changes in the concentration of the muddy slurry due to variation in the amounts of the excavated soil, fluc-

tuations in the resistance to flow in the water supply and exhaust lines due to changes in their length accompanying the progress of the excavation, or changes in the performance of the exhaust pump due to changes in the concentration of the muddy slurry, as well as in those cases where the operation of the exhaust pump ceases for emergency or other reasons. Again, the water head can be readily set in accordance with the conditions of the working face, and hence it becomes possible to carry out the pressurized-slurry sealed shield method of construction safely and with certainty.

I claim:

1. A method of controlling the water head supplied by a pump at the working face in a pressurized-slurry sealed shield method of construction, said method of controlling the water head comprising the steps of detecting the water head at the working face with a pressure transmitter, transmitting said water head as an electric signal to a pressure regulator, comparing said

5 electric signal with the set pressure at said regulator, converting the electric signal corresponding to the deviation between the first-named electric signal and said set pressure to a pressure signal, and transmitting said pressure signal as an excitation voltage to a variable-speed motor connected to the pumps and made up of an eddy current coupler and an induction motor to control the rotational speed of said variable speed motor, thereby changing the amount of water supplied by the pump.

10 2. The method according to claim 1 which comprises the steps of detecting the number of rotations of said variable-speed motor, feeding back said number of rotations as voltage, comparing said detected voltage with the set voltage, and adjusting the excitation voltage until the deviation becomes zero, thereby adjusting the number of rotations of said motor.
